UNITED STATES PATENT OFFICE.

GEORGE R. STANTON, OF DECATUR, ILLINOIS.

FOUNTAIN-BRUSH.

No. 848,700.

Specification of Letters Patent.

Patented April 2, 1907.

Application filed September 7, 1906. Serial No. 333,734.

To all whom it may concern:

Be it known that I, GEORGE R. STANTON, a resident of the city of Decatur, county of Macon, and State of Illinois, have invented 5 certain new and useful Improvements in Fountain-Brushes, of which the following is a specification.

One object of this invention is to provide simple and practical means for continuously 10 supplying a cleaning or scrubbing brush with water, and another object is to prevent the water from running down along the handle from the brush to the hands of the user.

The invention is exemplified in the structure hereinafter described, and it is defined 15 in the appended claims.

In the drawings forming part of this specification, Figure 1 is an illustration of the entire device on a reduced scale, and Fig. 2 is a 20 section through the brush on a larger scale.

The brush comprises the head or stock 1 and the bristles 2 or their equivalent. The head 1 has a bore 3 from front to back or from outside to inside. A plate 4 is secured 25 to the back of the brush by screws 5 or their equivalent, and it has a tubular extension 6, which extends through or into the bore of the brush-head. The tubular extension 6 has the wall 7 at its front end, and said wall is 30 finely perforated to form a sprayer. A nipple 8 is formed on the external rear surface of plate 4, in alinement with the tubular extension 6, and the nipple is screw-threaded to a standard size to provide for attachment of 35 the end 9 of the tubular handle. A washer or gasket 10 may be used between the plate 4 and the end of the handle for the purpose of forming a perfect joint.

The handle 9^c is here shown as a straight 40 tube of some considerable length connected at its lower end by a cock 12 with a hose 11, which supplies the water. Near the upper end the handle is given a turn 9^b, here shown as at a right angle, and then given a reverse 45 turn 9^a, here shown as greater than a right angle. The compound turn thus formed produces a depending elbow at the point 9^a, and in the ordinary use of the device for washing windows such dirty water as runs 50 down the end 9 will drip from the elbow 9^a rather than run up hill over the turn 9^b and down the handle 9^c to the operator's hand. I consider it advisable that the angle of the turn 9^a should be greater than that of the

turn 9^b, for the end 9 is thereby caused to 55 stand oblique to the handle 9^c and the bristles are neither in line with the handle nor at right angles thereto. If the bristles stand oblique, as shown, the brush can be used on all parts of an upright window as far as the 60 device will reach, and at no time will the operator stand beneath the brush-head, where the water would drip on him, or will the water run down the handle. Moreover, with the bristles oblique the operator can wash an 65 overhead glass, such as a skylight, and yet the drippings will not fall on him, because he does not stand beneath the brush-head.

In using the invention the brush is manipulated by the handle in an obvious manner, 70 while water is supplied in any desired quantity through the hose, the cock, the handle, and the sprayer penetrating the brush-head. The supply of water is continuous. The drip cannot reach the hands of the user, and so 75 the cleaning may proceed rapidly, easily, and without discomfort.

The construction has particular reference to simplicity and practicability, and the result is a brush that will properly perform its 80 function without being expensive to make.

As a matter of preference the plate 4, the tubular extension 6, and the nipple 8 are integral or cast in one piece; but this is a matter of convenience only, and I do not confine 85 myself to this particular mode of construction. So, also, the turns in the handle are preferably made by bending, while it is obvious that they may be otherwise formed without departing from the principle involved. 90 The brush, the handle, and the various details may be of any desired shape and proportion consistent with the terms of the claims.

Having thus described my invention, I claim as new and desire to secure by Letters 95 Patent—

1. In a fountain-brush, the combination with the brush-head having a water-passage; of a water-supply, and a tubular handle connecting the supply with the brush-head and given a compound turn near the latter so that the bristles stand oblique to the line of the handle, as and for the purposes set forth.

2. In a fountain-brush, the combination with the brush-head having a water-passage; of a water-supply, and a tubular handle connecting the supply with the brush-head, and given two turns near the latter for the pur-

pose set forth, the angle of the turn adjacent to the brush-head being greater than the angle of the other turn.

3. In a fountain-brush, the combination
5 with the brush-head having an axial water-
passage therethrough, and a tube fixed there-
in and provided with a sprayer; of a hose, a
cock, connected therewith, and a tubular
10 handle connecting the cock with said tube in
the brush-head, the body of the handle near

the brush-head being given first a right-ang-
ular turn and then an oblique turn in the
reverse direction, for the purpose set forth.

In testimony whereof I sign my name in
the presence of two subscribing witnesses.

GEO. R. STANTON.
